UNITED STATES PATENT OFFICE.

TREVA MEREDITH COOPER, OF DES MOINES, IOWA.

DESIGN FOR A MAIL BOX.

Application filed August 6, 1928. Serial No. 27,731. Term of patent 3½ years.

To all whom it may concern:

Be it known that I, TREVA MEREDITH COOPER, a citizen of the United States, and a resident of Des Moines, in the county of Polk and State of Iowa, have invented a certain new, original, and ornamental Design for a Mail Box, of which the following is a specification, reference being had to the accompanying drawing, forming part thereof.

The ornamental design for a mail box, as shown.

Des Moines, Iowa, July 27, 1928.

TREVA MEREDITH COOPER.
